KEY HOLDER

Manuel Castro, Canton, Ohio

Application January 12, 1954, Serial No. 403,474

6 Claims. (Cl. 70—456)

The invention or discovery relates to key holders for holding one or more keys, each key having a holed head of disklike formation such as is included in the key of a usual cylinder lock for an automobile door and ignition, or for a house or office door, or for other closure or mechanism.

To have satisfactory characteristics, such a key holder should:

- (1) Conceal the identification number of each key on the holder;
- (2) Be small in size and light in weight;
- (3) Make no sound when loaded with one or more keys, and carried in the pocket or other receptacle, and when in use;
- (4) Be of a construction rendering it impossible for a key to be lost from the holder;
- (5) Keep the keys on the holder always in order, so as to make it easy to choose any particular key for use;
- (6) Help by its form the operation of a key on the holder when used to operate the lock fitted by the key;
- (7) Maintain its relative position with respect to any particular key on the holder when the key is inserted in the fitting keyhole;
- (8) Enable disengagement of one or more keys from the holder without disengaging the keys remaining on the holder;
- (9) Hold one or a number of keys; and
- (10) Be made preferably in one piece, or by a limited number of separate parts or assemblies, so as to be durable in use.

As known to the present inventor, key holders generally available prior to the present improvements have each been lacking in a number of the foregoing enumerated characteristics.

Accordingly, the objects of the present invention or discovery include the provision of a new and improved key holder construction, preferably having each and all of the foregoing enumerated characteristics.

A further object of the present invention or discovery is to provide such a new and improved key holder construction having a simplified construction and arrangement of parts, permitting economical manufacture, and minimized cost to the user.

The foregoing and other objects are attained by the key holder construction, parts, combinations, and sub-combinations, which comprise the present invention or discovery, and the nature of which is set forth in the following general statement, and preferred embodiments of which together with their mode of use are set forth in the following description, and which are particularly and distinctly pointed out and set forth in the appended claims forming part hereof.

The nature of the present invention or discovery may be stated in general terms as embodying in one form, a key holder construction including adjacent portions or assemblies, each including a plurality of members, the adjacent portions or assemblies having a connection with

2

each other permitting swinging of the portions or assemblies with respect to each other between closed or interengaged positions, and open or disengaged positions, the closed positions being the normal key holding positions, and the open positions being those permitting addition or removal of one or more keys from the holder.

By way of example, embodiments of the new and improved key holder construction and component parts of the present invention or discovery are illustrated in the accompanying drawing forming part hereof, in which:

Fig. 1 is a front elevational view of a first embodiment of the improved key holder construction of the present invention or discovery, the adjacent portions or assemblies being shown in their closed positions;

Fig. 2 is a side elevational view thereof, looking in the direction of the arrows 2—2, Fig. 1;

Fig. 3 is a rear elevational view thereof, looking in the direction of the arrows 3—3, Fig. 2;

Fig. 4 is a plan view of a one-piece blank from which the first embodiment of the improved key holder construction is preferably made;

Fig. 5 is a front elevational view of a second embodiment of the improved key holder construction hereof, the adjacent portions or assemblies being shown in their closed positions;

Fig. 6 is a side elevational view thereof, looking in the direction of the arrows 6—6, Fig. 5;

Fig. 7 is a view similar to Fig. 6, showing the adjacent portions or assemblies in their open positions, and keys loaded on one of the adjacent portions or assemblies;

Fig. 8 is a plan view of a one-piece blank from which one of the adjacent portions or assemblies of the second embodiment of the improved key holder construction is preferably made;

Fig. 9 is a plan view of a one-piece blank from which the other adjacent portion or assembly of the second embodiment of the improved key holder construction is preferably made;

Fig. 10 is a front elevational view of a third embodiment of the improved key holder construction hereof, the adjacent portions or assemblies being shown in their closed positions;

Fig. 11 is a side elevational view thereof, looking in the direction of the arrows 11—11, Fig. 10;

Fig. 12 is a view similar to Fig. 11, showing the adjacent portions or assemblies in their open positions; and

Fig. 13 is a view similar to Fig. 10, showing a number of keys mounted on the third embodiment of the improved key holder, one of the keys being shown in extended position ready for use, and the other keys being shown in semi-closed positions in the holder.

Similar numerals refer to similar parts throughout the several views of the drawing.

A first embodiment of the improved key holder of the present invention or discovery is illustrated in Figs. 1 to 4 inclusive, and indicated generally by 10. The improved key holder 10 has a shape which is generally that of a rectangular box, and includes a side portion 11a and a side portion 11b which are swingable with respect to each other, and which interengage with each other, as hereinafter described in detail.

The holder side portion 11a includes an elongated side member 11a-1 which, as shown, is in the form of an elongated flat strip, one portion of which extends at right angles from a side edge of a shorter triangular back member 11a-2, which has a base end located intermediate the ends of the elongated side member 11a-1.

Beyond the triangular back member 11a-2 there extends from one end of the elongated side member 11a-1, a transverse key holding shank member 11a-3 which, as shown, is in the form of a flat strip having the same transverse cross section as the elongated side member 11a-1,

the wider faces of the flat strip members 11a-1 and 11a-3 being perpendicular to each other, and the edges of the flat strip members 11a-1 and 11a-3 lying in the same planes.

From the outer end of the transverse key holding shank member 11a-3, there extends a lock hook member 11a-4 which, as shown, is a flat strip member, and has wider faces parallel with the wider faces of the side member 11a-1, and extending in the same direction from the transverse key holding shank member 11a-3.

Similarly, the holder side portion 11b includes an elongated side member 11b-1 which, as shown, is in the form of an elongated flat strip, one portion of which extends at right angles from the side edge of a shorter back member 11b-2, which has a base located intermediate the ends of the elongated side member 11b-1.

Beyond the triangular back member 11b-2 there extends from one end of the side member 11b-1, a transverse key holding shank member 11b-3 which, as shown, is in the form of a flat strip having the same transverse cross section as the elongated side member 11b-1, the wider faces of the flat strip members 11b-1 and 11b-3 being perpendicular to each other, and having the same width as the members 11a-1 and 11a-3.

The apex ends of the triangular back members 11a-2 and 11b-2 are connected by a spring hinge member 12 which, as shown, is in the form of a flat strip.

In the normal closed position of the interengaging holder side portions 11a and 11b, the outer wider face of the key holding shank member 11b-3 abuts the inner wider face of the key holding shank member 11a-3, and the lock hook member 11a-4 hooks over the outer end of the side member 11b-1.

For the purposes of the present invention or discovery, the holder side portions 11a and 11b may be swung out of engagement with each other, whereby keys having holes in their ends, such as automobile ignition lock keys, and door lock keys of similar type, may be inserted on the key shank member 11b-3, slid therefrom onto the free portion of the elongated side member 11b-1 beyond the back member 11b-2, after which the holder side portions 11a and 11b are allowed to swing into engagement with each other, as shown in Figs. 1, 2 and 3, when the holed ends of the keys may then be slid on to the interengaged shank members 11a-3 and 11b-3, thereby locking the interengaged shank members, and preventing separable swinging of the key holder side portions 11a and 11b.

Preferably as shown, the holder side portion 11a mounts key clamp means in the form of an L-spring 13 which includes a long leg member 13-1 extending angularly from the apex end of the back member 11a-2 and the adjacent end of the side member 11a-1 to a location of the outer extremity of the long leg member 13-1 adjacent the inner corner between the side member 11b-1 and the shank member 11b-3.

The L-spring 13 also includes a short leg member 13-2 which extends along the inside of a short extension 11a-5 of the side member 11a-1 of the holder side portion 11a, said extension 11a-5 extending beyond the apex end of the back member 11a-2 towards the apex end of the back member 11b-2, and a connector 14 joins the L-spring short leg member 13-2 to the side member extension 11a-5.

Preferably, according to the present invention and discovery, all of the members of the portions 11a and 11b of the improved key holder 10 are formed in a one-piece blank 15 as shown in Fig. 4, which is formed to the final shape and arrangement of the several individual members, by bends made on the dash lines on the blank 15 as shown in Fig. 4.

A second embodiment of the improved key holder of the present invention or discovery is illustrated in Figs. 5 to 9, and indicated generally by 110. The improved key holder 110 has a shape which is generally that of a rec-

tangular box, and includes a side portion 111a and a side portion 111b which are swingable with respect to each other, and which interengage with each other, as herein-after described in detail.

5 The holder side portion 111a includes an elongated side member 111a-1 which, as shown, is in the form of an elongated flat strip, one portion of which extends at right angles from a side edge of a shorter rectangular back member 111a-2, which has one end located adjacent the mid-portion of the elongated side member 111a-1.

Beyond the rectangular back member 111a-2, there extends from one side edge of the elongated side member 111a-1, a transverse key holding shank member 111a-3 which, as shown, is in the form of a flat strip having the same transverse cross section as the elongated side member 111a-1, the wider faces of the flat strip members 111a-1 and 111a-3, and also the edges thereof being perpendicular to each other.

From the outer end of the transverse key holding shank member 111a-3, there extends a stop member 111a-4 which is in the form of an extension of the member 111a-3 and bent at right angles thereto.

At its side edge opposite and parallel to the side edge connected with the side member 111a-1, the back plate 25 111a-2 is formed with a hinge plate member 111a-6, which as shown is a longitudinally extending flange parallel with the side member 111a-1.

The holder side portion 111b includes an elongated side member 111b-1 which, as shown, is in the form of an elongated flat strip, and from one end of which extends a transverse key holding shank member 111b-3 which, as shown, is also in the form of a flat strip having the same transverse cross section as the side member 111b-1, the wider faces of the flat strip members 111b-1 and 111b-3 and also the edges thereof being perpendicular to each other, and having the same width as the members 111a-1 and 111a-3.

The end of the member 111b-1 opposite the end from which the shank member 111b-3 extends, is in the form of an offset hinge plate member 111b-5 which abuts the inner end of the hinge plate member 111a-6, and is connected thereto by a hinge pin 112.

In the normal closed position of the interengaging holder side portions 111a and 111b, the outer wider face of the key shank member 111b-3 abuts against the inner wider face of the key shank member 111a-3, and the lock hook member 111a-4 hooks over the outer end of the side member 111b-1, as shown in Figs. 5 and 6.

50 Preferably as shown, the holder side portion 111a mounts key clamp means in the form of an L-spring 113 which includes a long leg member 113-1 extending angularly from the outer end of the back member 111a-2 and the adjacent end of the side member 111a-1 to a location of the outer extremity of the long leg member 113-1 adjacent the stop member 111a-4.

The L-spring 113 also includes a short leg member 113-2 which extends along the inside of a short extension 111a-5 of the side member 111a-1 of the holder side portion 111a, said extension 111a-5 extending alongside of the outer edge of the back member 111a-2 towards the hinge plate member 111a-6, and a connector 114 joins the L-spring short leg member 113-2 to the side member extension 111a-5.

65 Preferably, according to the present invention and discovery, all of the members of the portion 111a of the improved key holder 110 are formed in a one-piece blank 115 as shown in Fig. 8, which is formed to the final shape and arrangement of the several individual members, by bends made on the dash lines on the blank 115 as shown in Fig. 8.

Similarly, all of the members of the portion 111b of the improved key holder 110 are formed in a one-piece blank 116 as shown in Fig. 9 which is formed to the final shape and arrangement of the several individual

members, by bends made on the dash lines on the blank 116 as shown in Fig. 9.

A third embodiment of the improved key holder of the present invention or discovery is illustrated in Figs. 10 to 13 inclusive, and indicated generally by 210. The improved key holder 210 has a shape which is generally that of a rectangular box, and includes a side portion 211a and a side portion 211b which are swingable with respect to each other, and which interengage with each other as hereinafter described in detail.

The holder side portion 211a includes an elongated side member 211a-1 which, as shown, is in the form of an elongated flat strip, one portion of which extends at right angles from the side edge of a shorter rectangular back member 211a-2 which has one end located adjacent the mid-point of the elongated side member 211a-1.

Beyond the rectangular back member 211a-2, there extends from one side face of the elongated side member 211a-1, a transverse key holding shank member 211a-3 which, as shown, is in the form of a flat strip having the same transverse cross section as the elongated side member 211a-1, the wider faces of the flat strip members 211a-1 and 211a-3 and also the edges thereof being perpendicular to each other.

From the outer end of the transverse key holding shank member 211a-3 there extends a stop member 211a-4 which is in the form of an extension of the member 211a-3 and bent at right angles thereto.

At its side edge opposite and parallel to the side edge connected with the side member 211a-1, the back plate 211a-2 is formed with a hinge plate member 211a-6 which, as shown, is a short flange parallel with the side member 211a-1.

The holder side portion 211b includes an elongated side member 211b-1 which, as shown, is in the form of an elongated flat strip, one portion of which extends at right angles from a side edge of a shorter rectangular back member 211b-2 which has one end located adjacent the mid-portion of the elongated side member 211b-1.

Beyond the rectangular back member 211b-2, there extends from one end of the side member 211b-1 a transverse key holding shank member 211b-3, which as shown is in the form of a flat strip having the same transverse cross section as the side member 211b-1, the wider faces of the flat strip members 211b-1 and 211b-3 and also the edges thereof being perpendicular to each other, and having the same width as the members 211a-1 and 211a-3. From the outer end of the transverse key holding shank member 211b-3 there extends a lock hook member 211b-4, which is an extension of the member 211b-3 and bent at right angles thereto.

At its side edge opposite and parallel to the side edge connected with the side portion 211b-1, the back plate 211b-2 is formed with a hinge plate member 211b-5 which, as shown, is a short flange parallel with the side member 211b-1.

The holder side portion 211a and the holder side portion 211b have their hinge plate members 211a-6 and 211b-5 abutting each other and connected with each other by hinge pin 212.

In the normal closed position of the interengaged holder side portions 211a and 211b, the inner wider face of the key shank member 211b-3 abuts against the outer wider face of the key shank member 211a-3, and the lock hook member 211b-4 hooks over the outer end of the side member 211a-1 as shown in Figs. 10, 11, and 13.

Preferably as shown, the holder side portion 211a mounts key clamp means in the form of an L-spring 213 which includes a long leg member 213-1 extending angularly from the outer end of the back member 211a-2 and the adjacent end of the side member 211a-1 to a location of the outer extremity of the long leg member 213-1 adjacent the stop member 211a-4. The L-spring 213 also includes a short leg member 213-2 which ex-

5 tends along the inside of a short extension 211a-5 of the side member 211a-1 of the holder side portion 211a, said extension 211a-5 extending alongside of the outer edges of the back member 211a-2 and 211b-2, and rivet connectors 214 join the L-spring short leg member 213-2 to the side member extension 211a-5.

10 Preferably, according to the present invention and discovery, all of the members of the portion 211a of the improved key holder 210 are formed in a one-piece blank, not shown.

Similarly, all of the members of the portion 211b of the improved key holder 210 are formed in a one-piece blank, not shown.

15 It is noted that each of the key holders, 10, 110, and 210, thus includes two laterally spaced longitudinally extending side members, a hinge connection between the side members, each side member having a key holding shank member extending towards the other side member, the key holding shank members extending alongside each other preferably in parallel side-by-side aligned engagement or abutment in their closed position, and being swingable to open positions in which the shanks are spaced from each other, whereby one of the shanks of each key holder may be inserted into the hole of one or more keys, each key being then slid from the shank onto the free portion of the connecting elongated side member, after which the side members and shanks are swung to the closed position with the shanks in side-by-side alignment with each other, and then the holed ends of the keys are slid onto the aligned side-by-side shank members, the aligned side-by-side shank members being locked by the key ends located thereon and being prevented from swinging to the open position.

20 In the key holders, 10, 110 and 210, there are furthermore preferably provided, respectively, lock hook members 11a-4, 111a-4, and 211b-4, each lock hook member being on the end of one of the shank members, each lock hook member in the closed position of the holder members, hooking over an outer end portion of the other elongated side member at the corner junction of the other elongated side member and the other shank member.

25 Moreover, the key holders, 10, 110 and 210, include, respectively, the springs 13, 113 and 213, each of which functions to maintain the holed key ends in spring-pressed abutment with each other and the elongated side member opposite the spring, thereby attaining certain of the objects of the invention.

30 Each of the key holders, 10, 110 and 210, has each and all of the above set forth characteristics required for a satisfactory key holder, and thus attain the stated objects of the invention.

35 In the foregoing description, certain terms have been used for brevity, clearness, and understanding, but no unnecessary limitations are to be implied therefrom beyond the requirements of the prior art, because such words are used for descriptive purposes herein and are intended to be broadly construed.

40 Moreover, the embodiments of the improved construction illustrated and described herein are by way of example, and the scope of the present invention is not limited to the exact details of construction.

45 Having now described the invention, the construction, the operation and use of preferred embodiments thereof, and the advantageous new and useful results obtained thereby; the new and useful constructions, and reasonable mechanical equivalents thereof obvious to those skilled in the art, are set forth in the appended claims.

50 I claim:

55 1. Key holder construction including two laterally spaced longitudinally extending side members, a hinge connection between the side members, each side member mounting a key holding shank member extending angularly from the side member towards the other side member, the side members with the shank members being swingable about the hinge connection between a closed

position of the shank members and an open position of the shank members, each key holding shank member extending in side-by-side alignment with the other in the closed position and being spaced from the other in the open position of the shank members, whereby one or more keys each having a holed end may have one of the shank members inserted in the holed end of each key, and each key may be moved onto one of the side members, and whereby in the closed position of the shank members each key may be moved onto the side-by-side shank members thereby locking the side members against opening movement, and one of the side members having a back member extending laterally therefrom towards the other side member, the back member having an end adjacent to and spaced from the shank member on the side member mounting the back member.

2. Key holder construction as set forth in claim 1, and in which one of the shank members has a lock hook member extending angularly therefrom and engaging the other side member in the closed position of the members. 20

3. Key holder construction as set forth in claim 1, and in which a flat spring is located between the side members and has a connection with one of the side members and extends towards the other side member, said other side member being the side member receiving and mounting the keys in the open position of the members, whereby in the closed position of the members the keys on the 25

side-by-side shank members are pressed by the spring toward the other side member.

4. Key holder construction as set forth in claim 1, and in which a back member extends laterally from the other side member and each side member includes a free portion which extends longitudinally from its back member, and in which the shank member on each side member extends from the free portion of the side member, and in which each back member mounts a part of the hinge 10 connection.

5. Key holder construction as set forth in claim 4, and in which each side member and the shank member and the back member extending therefrom is formed from a single piece of sheet metal.

6. Key holder construction as set forth in claim 5, and in which all the members and the hinge connection are formed from a single piece of sheet metal.
